SAFETY STOP FOR ELEVATORS

Filed Aug. 5, 1931

4 Sheets-Sheet 2

A technical drawing of a vertical assembly, likely a component of a larger machine. The assembly consists of a central vertical column with a grid pattern on its side. At the top, there is a horizontal plate with several components labeled 17, 19, 15, 31, 14, 32, and 27. A vertical pipe or tube extends from the top of the column. The bottom of the column features a horizontal plate with a small number 6 written on it. The entire assembly is set against a background of vertical lines, possibly representing a wall or a series of panels.

UNITED STATES PATENT OFFICE

TOM DONEFF, OF BURNHAM, PENNSYLVANIA

SAFETY STOP FOR ELEVATORS

Application filed August 5, 1931. Serial No. 555,290.

The present invention relates generally to elevators and more particularly for means to stop the elevator should the same start to fall because of a broken cable or the like and the object of the invention resides in the provision of a mechanism in the form of a safety stop which is simple in its construction, thoroughly efficient in use and operation, compact and convenient in its arrangement of parts and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

20 Figure 1 is a front elevation of an elevator frame showing my improved mechanism associated therewith.

Figure 2 is a side elevation thereof.

25 Figure 3 is a rear elevation of the upper portion of the frame showing the mechanism in released position.

Figure 4 is a similar view showing the mechanism in engaged position.

Figure 5 is a top plan view thereof.

30 Figure 6 is another top plan view showing portions of the frame in section, and

Figure 7 is a perspective view of a lever.

Referring to the drawings in detail it will be seen that numerals 5 denote the rails of the elevator shaft and numeral 6 denotes generally the elevator frame which includes side members 7, a cross top member 8 centrally located and a cross member 9 to one side thereof. Numerals 10 denote a pair of plates extending between the sides 7 at their upper ends under the cross member 8. Numeral 11 denotes a crank shaft journaled in a bearing 12 located between the plates 10 under the intermediate portion of the cross member 8 and includes adjacent one end a pair of cranks 14 and adjacent the other end a pair of cranks 15.

The cranks 14 are located on opposite sides of the axis of the shaft 11 while the cranks 15 extend to one side thereof. An arm 16 is

fixed to one end of the crank shaft 11 and has a weight element 17 on the extremity thereof which normally gravitates downwardly but is held in a raised position by a finger 18 engaging an intermediate portion of the lever 16 adjacent the weight element. This finger 18 projects laterally from a lever 19 of angular construction having an intermediate portion rockably mounted as at 20 on one of the plates 10 and an offset extremity at the other end thereof as at 21. Numeral 22 denotes an angularly constructed lever pivotally mounted as at 23 on the last mentioned plate 10 and having an offset extremity 24 to engage over top of the inner end of the lever 19. A spring 25 is engaged with the arm 16 adjacent the weight 17 and is anchored on a bracket 26 projecting inwardly from one of the sides 7 to yieldably retain the arm 16 in the position shown in Figure 4.

Numeral 27 denotes a hoisting cable of the elevator and a cable or the like 28 is engaged therewith and engaged with the outer end of the lever 22. When the cable 27 is taut as shown in Figure 3, then the levers 22 and 19 are disposed as to hold the weight element and its lever in an upward position but should the cable 27 become slack for any reason this permits the weight element to gravitate downwardly and turn the crank shaft.

Numerals 30 denote serrated faced shoes slidable through sides 7 below the top of the frame. Numerals 31 denote serrated faced shoes slidable through the upper end portions of the sides 7. Links 32 are engaged on cranks 14 and are pivotally engaged with the shoes 31 while links 32' are engaged on cranks 15 and with the shoes 30. Now when the crank shaft 11 is in the position shown in Figures 1 and 3 the shoes are disposed in retracted position out of engagement with the rails 5 but when the crank shaft is in the position shown in Figure 4 then the shoes are forced outwardly into engagement with the rails to cause the stopping of the elevator on the downward movement.

It is thought that the construction, operation, utility and advantages of this invention will now be quite apparent to those skilled

in this art without a more detailed description thereof.

The present embodiment of the invention has been described in considerable detail merely for the purposes of exemplification since in actual practice it attains the features of advantage enumerated as desirable in the statement of the invention and the above description.

10 It will be apparent that changes in the details of construction, and in the combination and arrangement of parts may be resorted to without departing from the spirit or scope of the invention as hereinafter claimed or sacrificing any of its advantages.

15 Having thus described my invention, what I claim as new is:

1. In combination, a pair of elevator shaft rails, a frame between the rails, said frame including side members, shoes slidable in the side members to engage the rails, a crank shaft having cranks, rods engaged with the cranks and with the shoes, a lever projecting from the crank shaft and having a weight on the outer end thereof tending to normally rock the shaft for engaging the shoes with the rail, a lifting cable for the frame, means operatively disposed between the cable and the lever permitting the lever to gravitate downwardly when the cable is slack but otherwise holding the lever upwardly.

2. In combination, a pair of elevator shaft rails, a frame between the rails, said frame including side members, shoes slidable in the side members to engage the rails, a crank shaft having cranks, rods engaged with the cranks and with the shoes, a lever projecting from the crank shaft and having a weight on the outer end thereof tending to normally rock the shaft for engaging the shoes with the rail, a lifting cable for the frame, means operatively disposed between the cable and the lever permitting the lever to gravitate downwardly when the cable is slack but otherwise holding the lever upwardly, said means comprising a pair of levers rockable on the frame and having inner ends one overlapping the other, the outer end of one of the levers having a finger to engage under the weighted lever, and a connection between the outer end of the other lever and the cable.

In testimony whereof I affix my signature.
TOM DONEFF.
